UNITED STATES PATENT OFFICE.

PAUL H. CRAGO, OF FOREST HILLS BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

CAR-OPERATED SWITCHING MECHANISM.

Application filed October 7, 1926. Serial No. 140,029.

My invention relates to car operated switching mechanisms, and particularly to car controlled means for operating switches on electric railways.

5 One object of my invention is to provide means for controlling a standard switch and lock mechanism from a trolley contactor.

I will describe three forms of switching mechanism embodying my invention, and will 10 then point out the novel features thereof in claims.

In the accompanying drawings, Fig. 1 is a diagrammatic view showing one form of switch operating mechanism embodying my 15 invention. Figs. 2 and 3 are views showing modifications of the apparatus shown in Fig. 1, and also embodying my invention.

Similar reference characters refer to similar parts in each of the several views.

20 Referring first to Fig. 1, the reference character 1 designates a trolley conductor which is placed in proximity to an electric railway designated by the reference character T and having a turn-out to a reverse route K controlled by a switch S. The switch S is shown in the normal position so that a car passing along the railway T in the direction shown by the arrow will continue on the main line. When switch S is reversed a passing car will 25 take the reverse route K.

The switch S is controlled by a motor M which receives its energy from the conductor 1 under conditions which will be described later. Associated with the motor M and switch S are two motor cut-out controllers O and W. The contacts 20, 21 and 22 of the controller O are closed at all times except when switch S is in full normal position. Contacts 23, 24 and 25 of controller W are 30 closed at all times except when switch S is in full reverse position.

In order that the switch S may be controlled by the operator of a car without stopping the car, a contactor C is mounted near but insulated from, the trolley conductor 1. Contactor C comprises two metal strips 2 and 2^a arranged to be bridged by the current collecting means on a passing car. The current collecting means is here shown as a trolley wheel 3 although obviously other means may be used.

Connected between the conductor 1 and the strip 2 of the contactor C is a current selective relay R having a front contact 28 and a back

contact 27. The relay R is so proportioned 55 that when the trolley wheel of a passing car bridges the contactor C with the controller of the car in the "on" position, front contact 28 of the relay will be closed, but if the controller of the passing car is in the "off" position the relay R will not pick up and the back contact 27 will remain closed. The relay R has such characteristics that the current which it receives due to current flowing through the car auxiliaries (lights, heaters 60 and air compressor) will be insufficient to cause it to pick up.

A neutral relay N has one of its terminals grounded at 6, and the other connected to the strip 2^a of contactor C through a high resistance 4 and a wire 5. The relay N has an armature A to which are secured contact fingers 29 and 30 and a locking detent 7. Also pivotally connected to armature A is a link L having a slot 31 adapted to engage a pin 32 on a pivoted arm 33. The arm 33 carries a contact finger 11, biased to the right hand, or open position by a compression spring 34 but held normally closed by the biased position of armature A. When the relay N is energized, contact 11 occupies the open position but when relay N is de-energized contact 11 is closed against the action of the spring 34.

The contacts 27 and 28 of the relay R control a polarized relay E. The relay E consists of three magnets 35, 36 and 37 which are arranged to actuate a polar armature P. The coils of magnets 35 and 37 are wound so that the armature P will be attracted by 85 which ever one of the magnets 35 or 37 is energized. Under some conditions it may be desirable to provide the magnet 36 with a permanent magnet core for the purpose of holding the armature P in the position to which it is last moved. The back contact 27 of relay R controls a circuit from conductor 1 through wire 8, high resistance 43, contact 40, contact finger 30 of relay N, contact 41, wire 42 and coils 35 and 36 of the relay E to ground at 38. When this circuit is closed the armature P is attracted to the normal position, as shown in the drawing. The front contact 28 of relay R controls a circuit from conductor 1, through wire 8, high resistance 90 39, contact 44, contact finger 29 of relay N, contact 45, wire 46 and coils 37 and 36 of relay E to ground at 38. When this circuit is 95 100 105

closed the armature P is thrown to the right hand position. Whenever the armature A is actuated due to energization of the relay N, detent 7 is raised to unlock the armature P. 5 When armature A drops, detent 7 locks armature P in either position, to which it has been moved by the relay E. Connected to the armature P is a link 47 to which are secured two circuit controllers X and Y for controlling the circuits of the motor M. When the springs 18 and 15 of circuit controllers X and Y, respectively, occupy their right hand positions, as shown, a circuit is closed through the motor M in one direction, and when the 15 springs 18 and 15 occupy their left-hand positions, a circuit for the motor M is closed in the reverse direction.

The motor M may be supplied with current from a separate source of either alternating 20 or direct current but is here shown as being supplied with current from the trolley conductor 1 by means of a potentiometer connection on a resistance 9. The resistance 9 has one end connected to the conductor 1 through 25 a wire 8, the other end being grounded at 48. When the relay N is de-energized with the armature P occupying its normal position, and with switch S in such position that contacts 20, 21 and 22 of cut-out controller O are closed, current will flow from the trolley conductor 1 through wire 8, resistance 9, contact 30 10, contact finger 11, contact 12, winding 13 of circuit breaker B, wire 14, spring 15 of circuit controller Y, wire 16, armature of motor M, wire 17, spring 18 of circuit controller X, wire 19, contacts 20, 21 and 22 of cut-out controller O and field winding F of motor M to ground at 50. When P occupies its reverse position with the switch S in such 40 position that contacts 23, 24 and 25 of the cut-out controller W are closed current will flow from the trolley conductor 1 through wire 8, resistance 9, contact 10, contact finger 11, contact 12, winding 13 of circuit-breaker B, wire 14, spring 18 of circuit controller X, wire 17, armature of motor M, wire 16, spring 15 of circuit controller Y, wire 26, contacts 25, 24 and 23 of cut-out controller W and field winding F of motor M to ground at 50. It will thus be seen that when the relay N is de-energized the position of the armature P determines the direction of the current flowing through the motor M.

The circuit breaker B is of the over-load type and since its structure is well known in the art and forms no part of my invention it will be sufficient to state that the armature 49 will be attracted to raise the link E, releasing the slot 31 from the pin 32 on arm 33 and thus allowing spring 34 to open the contact finger 11 when an abnormal current continues to flow through winding 13. With normal current flowing the parts occupy the positions in which they are shown.

65 In tracing the operation of the switching

mechanism I will assume that all parts occupy the normal position shown in the drawing and that a car is approaching the switch S on the track T in the direction indicated by the arrow. If the operator of the car desires to 70 take the reverse route he moves the car controller to the "on" position before the trolley wheel 3 bridges contact C. When the trolley wheel 3 bridges the strips 2 and 2^a, the circuit for neutral relay N is closed through 75 wire 8, relay R, strip 2, trolley wheel 3, strip 2^a, resistance 4, wire 5 and winding of relay N to ground at 6. When this circuit is closed the relay N picks up raising the detent 7 and opening the contact 10-11-12. Contact finger 30 connects contacts 40 and 41 and contact finger 29 connects contacts 44 and 45. The current which flows through relay R under these conditions is the current for relay N, the current for car auxiliaries and the car 80 operating current, which, due to the adjustment of relay R, will cause it to be picked up and closing its front contact 28. Current will now flow from the trolley conductor 1 through wire 8, front contact 28 of relay R, 85 resistance 39, contact 44, contact finger 29, contact 45, wire 46, and magnets 37 and 36 to ground at 38. When this circuit is closed the magnet 37 attracts armature P which has been previously unlocked by energization of 90 relay N, and circuit controllers X and Y are thrown to the left-hand or reverse position. When the trolley wheel 3 leaves the contactor C, relay N is de-energized and detent 7 locks 95 armature P in the reverse position. Contact 100 finger 29 is released from contacts 44 and 45, contact finger 30 is released from contacts 40 and 41 and the contact finger 11 bridges contacts 10 and 12. When the motor M starts to 105 rotate it moves the cut-out controllers O and W to the mid-position and moves the switch toward its reverse position. When the switch S reaches its full reverse position the cut-out controller W is opened to break the circuit for 110 the motor M.

If, with the switch S in its reverse position, another car approaches the switch S on the track T and the operator of the car wishes to follow the main route, he moves the controller to the "off" position. When the trolley wheel 115 3 strikes the contactor C under these conditions, no current will flow through relay R, except the current for relay N and the current for the car auxiliaries, so that back contact 27 will be closed to complete a circuit through the magnets 35 and 36, and throw armature P to the normal position. When the armature P moves to the normal position the circuit controllers X and Y are moved to the right hand position so that current will 120 flow through the motor M in such direction as to throw switch S to the normal position as shown in the drawing.

If the operator of a car desires to take the reverse route when the switch S is already 130

in the reverse position he moves the controller to the "on" position before the trolley wheel 3 bridges the strips of contactor C so that sufficient current will pass through relay R to 5 close the front contact 28 of this relay. Under these conditions the front contact 28 of relay R is closed and the magnets 37 and 36 of relay E are energized to hold the armature P in its reverse position. The contacts 10 25, 24 and 23 of cut-out controller W being open no current can be supplied to the motor M and therefore the switch S remains in its reverse position.

If the operator of a car approaching switch 15 S finds the switch in the normal position and desires to follow the main route he moves the controller to the "off" position before the trolley wheel 3 bridges the strips of contactor C, so that relay R does not close its front contact 28 but energizes the magnets 35 and 36 20 of relay E over back contact 27 of relay R. Under these conditions the cut-out controller O remains in its open position and no current can be supplied to the motor M. 25 It will now be clear that the heavy current circuits are separated from the switch controlling mechanism and that false operation is prevented by means of the polarized relay E which is locked in each position. It is also 30 obvious that the resistors leading from the trolley conductor to the switch operating mechanism may be mounted in any convenient place along the track and will fully protect the switch operating mechanism against 35 excessive currents.

The modification shown in Fig. 2 is similar to the form shown in Fig. 1 except that the relay R¹ has only a single front contact 52, neutral relay N carries only one spring finger 40 29 and polarized relay E¹ is controlled differently.

In Fig. 2 the polarized relay E¹ has three magnets 55, 56 and 62. Magnets 55 and 56 are controlled by the contactor 52 of relay R¹ 45 over a circuit from conductor 1, wire 8, contact 52 of relay R¹, resistance 53, wire 54, magnets 55 and 56 to ground at 57. The magnet 56 may have a permanent magnet core for holding the armature P in either 50 position to which it is attracted. Magnet 62 is opposite in polarity to magnet 55 and is controlled by contact finger 29 of neutral relay N. The circuit for magnet 62 is from conductor 1, through wire 8, resistance 58, 55 contact 59, contact finger 29 of relay N, contact 60, wire 61 and magnet 62 to ground at 63. The magnets 62, 56 and 55 are so arranged that energization of magnet 62 will 60 attract the armature P to the normal position (as shown), but when magnets 55 and 56 are energized simultaneously with 62 the armature P will be swung to the right-hand or reverse position.

The relay R¹ is adjusted so that the current flowing through the auxiliaries on a

passing car will not cause it to close its contact 52 but if a greater current is flowing due to the car controller being in the "on" position the contact 52 will be closed.

The details of the operation of the circuits 70 shown in Fig. 2 will be understood from the description given in connection with Fig. 1. When a car approaches the switch S in the position shown the operator will approach the contactor C with the car controller in the "off" position, if he wishes to take the main line T. If he wishes to take the reverse route K he will approach the contactor C with his controller in the "on" position. If the switch S is in the reverse position, and the operator on an approaching car wishes to take the main line, he will approach the contactor C with the car controller in the "off" position. 75

In the apparatus shown in Fig. 3, the use 80 of a current selective relay associated with the contactor C is avoided. In this view the strip 2^a of contactor C is connected with neutral relay N through a resistance 4, as before, but the strip 2 is connected to the trolley conductor 1 through a wire 64, magnet 65 of 85 a polarized relay E², and a wire 66.

The polarized relay E² consists of three 90 magnets 65, 75 and 76. Magnet 76 may have a permanent magnet core for holding the armature P in either of its positions. Magnet 65 is controlled by the bridging of the strips 95 2 and 2^a of contactor C by a trolley wheel. The magnet 65 is so arranged that the current drawn by the auxiliaries of a passing car will not be sufficient to actuate armature P from its normal position as shown, but when a greater current is drawn by the passing car, magnet 65 will over balance the magnets 75 and 76. Magnets 75 and 76 are controlled over contacts 70 and 71 of neutral 100 relay N which in this modification has only a single contact finger 29. The circuit for magnets 75 and 76 with E² in normal position is from trolley conductor 1, through wires 8 and 77, contact 71, contact finger 29, contact 105 70, wire 69, resistances 72 and 73, and magnets 75 and 76 to ground at 38. When this circuit is closed and current for the auxiliaries only of a car is being drawn from the conductor 1 the armature P is held in normal 110 position. If a car passes along with its controller in the "on" position and bridges strips 2 and 2^a, the current through 65 will be great enough to swing the armature P to the reverse position against the action of 115 magnets 75 and 76. The magnets 75 and 76 also have a branch circuit which will be described hereinafter.

The energization of magnet 65 is subject to 120 considerable variation as the auxiliaries of different cars may consume different amounts of current. It is essential that the armature P and circuit controllers X, Y and Z controlled thereby through link 47 shall not be moved from normal to reverse position by the heavy- 125

iest auxiliary current load of any car used over the switch S, and in order to prevent such a false operation I connect the normal contact of circuit controller Z to the conductor 1. 6 This connection provides a branch circuit from conductor 1, through wires 8 and 78, normal contact of circuit controller Z, wire 68, resistances 72 and 73, and magnets 75 and 76 to ground at 38. This circuit is closed at all 10 times when the armature is in its normal position and will prevent false operation of the relay. When the circuit controller Z is in the reverse position this branch circuit is open and magnets 75 and 76 are energized only 15 when neutral relay N closes the contact 70—29—71 as a result of the contactor C being bridged. In the reverse position the circuit controller Z also shunts out the resistance 72, by completing a circuit from conductor 1, 20 through wires 8 and 77, contact 71, contact finger 29, contact 70, wires 69 and 68, spring 67 of circuit controller Z, wire 74, resistance 73, and magnets 75 and 76 to ground at 38. This shunting action of the circuit controller 25 Z assists in throwing the armature P to normal position by causing a heavier current to flow through magnets 75 and 76 at the beginning of the stroke when the air gap between magnet 75 and armature P is large.

30 The motor M is controlled as in Fig. 1, and is here shown as being supplied with current by means of a potentiometer connection to resistance 9.

35 The operation of the mechanism in Fig. 3 is as follows: When a car approaches the switch S on track T with the switch in normal position and the controller of the car in the "on" position, the current drawn by the car sets up a flux in magnet 65 as soon as the trolley wheel bridges the contact strips 2 and 2^a of contactor C. Magnets 75 and 76 are already energized over the circuit including the normal contact of circuit controller Z and the resistances 72 and 73. When relay N picks up 40 another circuit for magnets 75 and 76 is completed from conductor 1, through wires 8 and 77, contact 71, contact finger 29, contact 70, wire 69, resistances 72 and 73, and magnets 75 and 76 to ground at 38. This energization of 45 magnets 75 and 76 is only sufficient to balance the flux produced in magnet 65 by the car auxiliary current, hence the flux due to motor current in 65 will be sufficient to move the armature P to the reverse position after the detent 7 is released by the energization of neutral relay N. As soon as the armature P commences 50 its movement toward the reverse position the normal contact of circuit controller Z is opened so that magnets 75 and 76 remain energized only until neutral relay N releases its armature A and contact finger 29 drops away from contacts 70 and 71. When the trolley wheel 3 leaves the contactor C the detent 7 of 55 armature A drops and locks the armature P in the reverse position, contact 10—11—12 is

closed and motor M is operated to throw switch S to the reverse position as already described in connection with Fig. 1.

If another car approaches the switch S and the operator desires to return the switch to 70 normal he operates his car past the contactor C with the controller in the "off" position so that only the current due to the car auxiliaries passes through magnet 65. Since the resistance 72 is shunted by circuit controller Z a 75 higher current will flow through magnets 75 and 76 during the beginning of the stroke before the shunt is opened by circuit controller Z, and armature P will be thrown back to the normal position after the detent 7 is raised 80 by energization of relay N. As soon as the shunt is opened the current for magnets 75 and 76 is smaller because it passes through both resistances 72 and 73, but it is still sufficient to overbalance the auxiliary current in 85 magnet 65, and armature P completes its movement. The reversal of circuit controllers X and Y will reverse the connections to the motor M, and when the trolley wheel leaves the contactor C the switch S will be thrown back to normal, the armature P having been locked by the de-energization of relay N.

If the operator of the car approaching the switch S reversed, had desired to take the reverse route K he would have operated his car past the contactor C with the controller in the "on" position.

Should an operator find the switch S in the normal position and desire to take the normal route T he would operate his car past the contactor C with the controller in the "off" position so that magnet 65 would receive only the current due to the car auxiliaries, hence armature P would not be moved.

Although I have herein shown and described only a few forms of switching apparatus embodying my invention, it is understood that various changes and modifications may be made therein within the scope of the 110 appended claims, without departing from the spirit and scope of my invention.

Having thus described my invention, what I claim is:

1. A car controlled switching mechanism 115 comprising, an energized conductor, a two-part contactor in spaced relation to the conductor, a current selective relay connected to one part of the contactor and to the conductor, a polarized relay having a two-position armature which assumes one position when the current selective relay is traversed by current of one value and another position when the current selective relay is traversed by a current of higher value, and a switch actuating motor controlled by the polarized relay when the two parts of the contactor are bridged.

2. A car controlled switching mechanism 120 comprising, an energized conductor, a two-

part contactor in spaced relation to the conductor, a current selective relay connected to one part of the contactor and to the conductor, and controlled in accordance with the strength of the current which flows through it when the two parts of the contactor are bridged, a polarized relay arranged to assume one position when the current selective relay is energized, and another position when the relay is de-energized, and a switch operating motor controlled by the polarized relay.

3. A car controlled switching mechanism comprising, an energized conductor, a two-part contactor spaced from the conductor, a current selective relay connected to one part of the contactor and to the conductor, a polarized relay having two positions, and arranged to assume one position or the other when the parts of said contactor are bridged according as the current selective relay is energized or de-energized, a switch actuating motor, and means controlled by the polarized relay for controlling the motor.

4. A car controlled switching mechanism comprising, an energized conductor, a current selective relay connected to the conductor, a polarized relay having two circuits one of which is closed only when the current selective relay is energized and the other of which is closed only when the current selective relay is de-energized, a two-position armature for the polarized relay arranged to assume one position or the other according as the current selective relay is energized or de-energized, and a switch actuating motor controlled by the polarized relay.

5. A car controlled switching mechanism comprising, an energized conductor, a two-part contactor in spaced relation to the conductor, a current selective relay connected to one part of the contactor and to the conductor, a polarized relay having two circuits controlled separately by the energization and de-energization of the current selective relay, a two-position armature for the polarized relay having its position determined by the condition of the current selective relay when the two parts of the contactor are bridged, and a switch actuating motor controlled by the armature.

6. A car operated switching mechanism comprising, a two-part contactor in spaced relation to the conductor, a current selective relay connected to one part of the contactor and to the conductor, a two-position armature, and means controlled by the current selective relay for shifting the said armature from one position to the other when the two parts of the contactor are bridged.

7. A car controlled switching mechanism comprising, an energized conductor, a two-part contactor in spaced relation to the conductor, a polarized relay having a movable armature, a locking device for the armature

controlled by the bridging of the parts of the contactor, and a switch actuating motor controlled by the relay.

8. A car controlled switching mechanism comprising, an energized conductor, a two-part contactor in spaced relation to the conductor, a polarized relay having a two-position armature, a device for normally locking the armature in either position and unlocking it only when the strips of the contactor are bridged, a current selective relay connected to one part of the contactor and to the conductor for determining the position of the armature when the strips of the contactor are bridged, and a switch actuating motor controlled by the armature.

9. A car controlled switching mechanism comprising, an energized conductor, a two-part contactor in spaced relation to the conductor, a polarized relay having a two-position armature, a device for normally locking the armature in either position, means controlled by the bridging of the parts of the contactor for unlocking the armature, and a switch actuating motor controlled by the relay.

10. In combination, a railway switch, an electric motor for causing reverse operations of said switch according as the motor is operated in one direction or the other, a polarized relay having an armature for causing operation of said motor in one direction or the other according as said relay is energized in one direction or the other, a conductor supplying propulsion current to the railway, and means for energizing said relay in one direction or the other from said conductor according as a car is or is not drawing propulsion current from said conductor while approaching said switch.

11. In combination, a railway switch, an electric motor for causing reverse operations of said switch according as the motor is operated in one direction or the other, means for opening the motor circuit when the movement of the switch to either position is completed, a polarized relay having an armature for causing operations of said motor in one direction or the other according as said relay is energized in one direction or the other, a conductor supplying propulsion current to the railway, and means for energizing said relay in one direction or the other from said conductor according as a car is or is not drawing propulsion current from said conductor while approaching said switch.

12. In combination, a railway switch, an electric motor for causing reverse operations of said switch according as the motor is operated in one direction or the other, a polarized relay having an armature which reverses its position according as said relay is energized in one direction or the other, means for reversing the armature connections but not the field connections to the motor when the arma-

ture of the relay is reversed, a conductor supplying propulsion current to the railway, and means for energizing said relay in one direction or the other from said conductor according as a car is or is not drawing propulsion current from said conductor while approaching said switch.

13. In combination, a railway switch, an electric motor for causing reverse operations of said switch according as the motor is operated in one direction or the other, means for opening the motor circuit when the movement of the switch to either position is completed, a polarized relay having an ar-

15 ture for causing operation of said motor in one direction or the other, according as said relay is energized in one direction or the other, a conductor supplying propulsion current to the railway, means for supplying current to the motor from said conductor, and means for energizing said relay in one direction or the other from said conductor according as a car is or is not drawing propulsion current from said conductor while approaching said switch.

20 In testimony whereof I affix my signature

25 PAUL H. CRAGO.
